US00D928189S

(12) **United States Design Patent** (10) Patent No.: **US D928,189 S**
Giannino et al. (45) Date of Patent: ** *Aug. 17, 2021

(54) **DISPLAY SCREEN WITH GRAPHICAL USER INTERFACE FOR MEDICAL TREATMENT AND/OR DIAGNOSTICS**

(71) Applicant: **Warsaw Orthopedic, Inc.**, Warsaw, IN (US)

(72) Inventors: **David R. Giannino**, Minneapolis, MN (US); **Nicholas M. Benson**, Collierville, TN (US); **Annie M. Mickelson**, Loretto, MN (US)

(73) Assignee: **Warsaw Orthopedic, Inc.**, Warsaw, IN (US)

(*) Notice: This patent is subject to a terminal disclaimer.

(**) Term: **15 Years**

(21) Appl. No.: **29/684,943**

(22) Filed: **Mar. 25, 2019**

(51) LOC (13) Cl. **14-04**

(52) U.S. Cl.

USPC **D14/486**; D14/495
